DESIGN FOR A COMBINATION MAGAZINE PENCIL AND LETTER OPENER

Adolf Kinzinger, Pforzheim, Germany

Application April 29, 1933. Serial No. 47,937

Term of patent 7 years

To all whom it may concern:

Be it known that I, ADOLF KINZINGER, a citizen of the German State, residing at No. 39 Jahnstrasse, Pforzheim, Germany, have invented a new, original, and ornamental Design for a Combination Magazine Pencil and Letter Opener, of which the following is a specification, reference being had to the accompanying drawing, forming part thereof.

In the accompanying drawing a combination magazine pencil and letter opener is shown in

Fig. 1 in front elevation and in Fig. 2 in side elevation. Fig. 3 is a plan view seen from below of Fig. 1 and Fig. 4 is a top plan view of Fig. 1, the clip element having been omitted in these two figures.

I claim:—

The ornamental design for a combination magazine pencil and letter opener substantially as shown.

ADOLF KINZINGER.
